UNITED STATES PATENT OFFICE.

JAMES G. MACLAREN, OF MAMARONECK, NEW YORK, AND WILLIAM J. HEPPERLE, OF BLOOMFIELD, NEW JERSEY, ASSIGNEES, BY MESNE ASSIGNMENTS, TO THE LAMSON COMPANY, A CORPORATION OF MASSACHUSETTS.

DELIVERY DEVICE FOR PNEUMATIC-DISPATCH TUBES.

Application filed February 18, 1922. Serial No. 537,418.

To all whom it may concern:

Be it known that we, JAMES G. MACLAREN and WILLIAM J. HEPPERLE, citizens of the United States, residing, respectively, at 5 Mamaroneck, in the county of Westchester and State of New York, and at Bloomfield, in the county of Essex and State of New Jersey, have invented certain new and useful Improvements in Delivery Devices for 10 Pneumatic-Dispatch Tubes, of which the following is a specification.

The present invention relates to conveyors and dispatch apparatus and particularly to an apparatus for receiving and disposing of 15 carriers in pneumatic dispatch apparatus. More specifically it relates to an apparatus by which carriers may be received by an operator or may at the will of the operator, be passed to a reserve operator.

20 In the operation of pneumatic dispatch apparatus, it is customary to direct carriers, containing money or other articles, from definite sources to a single operator, the work being so proportioned that each operator 25 normally receives a number of carriers which it is within her capacity to handle and dispose of. It sometimes occurs, however, that carriers are received by an operator at a rate considerably above the 30 normal and above that at which they can be conveniently taken care of by a single operator. When this occurs the excess or surplus carriers received above the normal rate must be transferred to a reserve operator if 35 delays and confusion are to be avoided.

An object of the present invention is to provide a simple cheap and compact apparatus by which carriers may be received by an operator or may be passed to a reserve 40 operator.

Another object of the invention is to provide a single unitary receiver which may serve either as a receptacle for arriving carriers or as a delivery terminal to transfer 45 carriers from the discharge end of a tube to a reserve operator.

With these and other objects in view, the invention comprises the apparatus described in the following specification and defined in 50 the claims.

The various features of the invention are illustrated in the accompanying drawing which is a view partly in elevation and partly in section of an apparatus comprising

a portion of a pneumatic tube, a belt conveyor and a receiver embodying a preferred form of the invention.

In the present invention the receiving element is movably positioned in relation to the discharge end of the pneumatic tube so that in one position it receives and holds the carriers at a point convenient for the operators and in another position discharges the overflow carriers to a reserve operator or to a conveying means by which they may be carried to a reserve operator. To this end the receiving element is preferably attached to the end of the discharge tube or chute by a collar rotatably mounted on the end of the tube in such a manner that the receiver may be rotated about the axis of the tube. The receiving portion of the receiver is so shaped or curved that when it is in one position, the carriers are deflected onto a belt conveyor leading to a reserve operator, and when it is in another position, the carriers are retained in a position convenient to the primary operator.

Referring more particularly to the accompanying drawings, the carriers 1 are discharged through a downwardly extending discharge tube or chute 2 into a curved receiver 3 which is rotatably supported on the end of the tube 2 by means of a collar 4 integral with the receiver and surrounding the end of the tube. The collar 4 is rotatably mounted on the tube so that it may be turned about the axis of the tube by the operator into the position shown in full lines or into the position shown in dot and dash line in the drawing. In the latter position the lower end of the receiver rests on a rim or ledge 6 of a bracket-shaped stop 7 which has an upwardly projecting rim or flange 8. The carriers discharged from the tube 2 slide down the curved portion of the receiver until they are stopped by the ledge 8 and are held on the receiver in a position convenient for their removal by the operator.

If the carriers are being discharged at a greater rate than they can be taken care of by the operator and form an unattended accumulation, the receiver may be rotated about the axis of the discharge tube into the position shown in the drawing in full lines. In this position of the receiver the carriers are directed to a reserve operator either di-

rectly or through a suitable conveying apparatus. In the embodiment of the invention shown in the accompanying drawing the end of the receiver rests on a ledge 9 forming an element of a conveying apparatus and the carriers are discharged from the receiver onto a belt conveyor 10 which conveys them to the reserve operator. The receiver may in this manner be rotated about the axis of the tube 2 by the operator to receive the normal supply of carriers or to direct the overflow to a reserve operator. When the operator has disposed of the accumulated carriers, the receiver may be rotated back to normal position until a new accumulation of unattended carriers is formed whereupon the receiver may be positioned to direct the overflow to the reserve carrier.

20 While the above form of the apparatus is preferred, it is obvious that any suitable form of conveying apparatus may be employed and that other changes in the form of embodiment and the arrangement of the 25 various parts of the apparatus may be made to suit any given conditions without departing from the broader features of the invention.

What we claim is:

30 1. In pneumatic dispatch apparatus, a dispatch tube, and a delivery nozzle for the discharge end of the tube adapted to be moved to different delivering positions while constantly maintaining its receiving end in cooperative relation to the discharge end of the dispatch tube.

40 2. In pneumatic dispatch apparatus, a dispatch tube, and a delivery nozzle for the discharge end of the tube, said delivery nozzle being rotatable to a plurality of delivering positions while constantly maintaining its receiving end in cooperative relation to the delivery end of the dispatch tube.

45 3. In pneumatic dispatch apparatus, a dispatch tube, and a delivery nozzle for the tube, said delivery nozzle being free to rotate and manually rotatable to a plurality of delivering positions.

50 4. In pneumatic dispatch apparatus, a dispatch tube, a delivery member pivotally mounted on the end of the tube and free to be turned to different delivery positions.

55 5. In pneumatic dispatch apparatus, a dispatch tube and a combined delivery and receiving member pivotally carried by the tube, said member being curved at its lower end and having a delivery opening in its

concave side, said member being free to rotate about the axis of the dispatch tube to a plurality of operating positions.

6. The combination with the discharge end of a pneumatic dispatch tube of a receiver adapted in one position to receive and hold a carrier and in another position to transfer carriers from said delivery tube to a removing means.

7. The combination with a delivery end of a pneumatic dispatch tube of a receiver manually movable into a position to receive and hold a carrier from said tube and into another position to transfer carriers from said tube to a removing means.

8. The combination with the discharge end of a pneumatic tube and a conveyor means, of a receiver rotatable about the axis of said tube and arranged in one position to hold carriers from said tube and in another position to transfer carriers from said tube to said conveyor means.

9. The combination with the discharge end of a pneumatic dispatch tube of a conveyor means, a stop and a curved receiver positioned to be rotated about the axis of said tube into engagement with said stop to receive and hold carriers from said tube and to be rotated about said axis to deliver carriers to said conveyor means.

10. The combination of a discharge end of a pneumatic dispatch tube, a conveyor means below said discharge end, a stop and a combined receiver and deflector rotatably connected to the end of said tube and adapted to be rotated into cooperative position with said stop to receive and retain carriers and to be rotated into another position to pass carriers from said tube to said conveyor means.

11. In a dispatch apparatus, the combination of a discharge tube, a receiver having a collar rotatably mounted on said tube, a conveyor means, said receiver being rotatable about said tube to a position to receive and hold a carrier from said discharge tube and to another position to pass carriers from said tube to said conveyor means.

12. In a pneumatic dispatch apparatus, the combination with the discharge end of a pneumatic dispatch tube, of a receiver rotatably mounted in relation to said tube and adapted in one position to receive and hold a carrier from said tube and in another position to pass carriers from said tube to a reserve operator.

JAMES G. MACLAREN.
